UNITED STATES PATENT OFFICE

EDWARD M. PENNOCK, OF MINNEAPOLIS, MINNESOTA

BOTTLE CRATE

Application filed August 15, 1927. Serial No. 212,956.

This invention relates to an improvement in bottle crates of the type used for milk bottles and of a similar nature. The primary feature of the invention resides in a means adapted to protect the bottles in the crate against breakage and consists in providing a resilient spacer between the bottles of a nature impervious to moisture.

It is also a feature of the invention to provide a spacing means of a thin sheet-like nature with side walls spaced apart so as to provide the necessary cushion between the base portions of the bottles so that when the crate with the bottles is slid along the floor of the creamery and these crates jam one against the other, the jar is absorbed in the crate between the bottles and the spacing means and the bottles are protected against breakage. When the crates are jammed together with the bottles in the same the jar causes the bottles to ride up against each other particularly at the base and this impact breaks the bottles in such a manner as to cut the bottoms off of the same. I have found that my improved crate overcomes this difficulty in a very practical manner.

It is also a feature of my crate to provide a compact spacing means between the rows of bottles which is adapted to form the necessary resiliency to prevent the bottles from striking each other either when the crates are jammed together or in handling the crates through the creamery and in delivery. I accomplish this in one form by providing a plate formed of sheet material which is bent over and carried by the partition wires in a manner to provide a space between the sides of the same which compensates for the necessary movement of the bottles in the crate and prevents breakage of the same.

These features together with other objects and details will be more fully and clearly set forth in the specification and claims.

In the drawing forming a part of this specification:

Figure 1 is a plan view of my crate.

Figure 2 is a side sectional view on the line 2—2 of Figure 1.

Figure 3 is a sectional view on the line 3—3 of Figure 1.

Figure 4 is an enlarged sectional detail.

Figure 5 is an enlarged sectional detail.

My crate A is made up of side members 10 and end members 11 which preferably are of wood in the form of slats superimposed in a manner to provide an outer casing or body portion for the crate A.

The ends of the sides 10 and 11 are connected together by the outer angle member 12 and the inner angle member 13 in a manner to rigidly connect the corners of the crate A together to provide a strong and sturdy construction which is adopted to stand the wear and tear in the use of the crate A. My crate A is particularly adapted for use with milk bottles B and is made of a construction adapted to withstand the wear and rough usage that these crates ordinarily receive in creameries where milk bottles are handled in these crates. It is desirable to provide a crate of a construction adapted to stand the washing of the bottles while they are held in the crates and the bottles are usually turned upside down in the crate while they are being washed. This requires a crate having the principal inner portions made of metal or other material impervious to water.

My crate A is provided with longitudinally extending partitions made up of the wire members 15 and transversely extending partitions made up of the wire members 16. The wire members 15 and 16 extend between the walls 10 and 11. These wire partitions take up only a small space in the crate A and at the intersection of the wire members 15 and 16 I provide angle iron reinforcing spacers 17 which hold the wires properly spaced apart and in position in relation to each other to permit the wire partitions to give slightly and yet be firm enough to hold and provide the partitions for the bottles B so as to separate the different bottle compartments C within the crate A.

Along the bottom of the crate A I pro-

vide pairs of parallelly extending wire members 18 which are spaced fairly close together and these wire members form the bottoms for the crate bottle compartments C. 5 The wires 18 are spaced close enough together so as to receive either the bottom of the bottles B or hold the top of the neck of the same resting upon the wires 18. When the bottles are cleansed in the crates A they are turned upside down with the neck resting on the wires 18.

I provide the resilient spacer members 20 which are made in the form of a plate of sheet metal or other suitable material impervious to water and moisture. The resilient member 20 is formed with side walls and in the construction of the same illustrated in Figure 4 the member 20 is extending in a virtually U-shaped form over the rods 16. The lower or free ends 22 of the walls 21 are adapted to extend below the rods 16 and the lower or bottom rods 18 pass through the side walls 21 of the member 20 freely so that the sides 21 may be moved together to provide resiliency between the sides so that the bottom portion 23 of the bottle B may bear against the side walls 21 when it shifts in the crate A. On the righthand side of the bottle compartment C in the detail illustrated in Figure 4, I have illustrated the side walls of the resilient plate member 20 extending almost parallel, while on the lefthand side of this figure I have illustrated the side walls 21 flaring outwardly. These resilient or compensating members 20 may be made in either form illustrated in this figure and it is obvious that the spreading of the side walls 21 as illustrated on the left side of Figure 4 merely 30 gives a little more compensation and provides a spring member against the sides of the portion 23 of the bottles B in the crate. 40

In Figure 5 I have illustrated the compensating plate member 20 of a corrugated nature and having its ends bent around the rods 15. I have also shown this corrugated construction attached in one of the bottoms of the compartment C in Figure 2 to simply 45 show the position of the same if it is desired to use these compensating plates on the longitudinal partition rods 15. I have found that ordinarily it is not necessary to use the compensating plates 20 on the longitudinal partitions 15, however, they can be used in 55 the same manner on this partition as they are used on the partition rods 16.

I have found that milk bottles, owing to their shape and nature, usually strike at the bottoms 23, one against the other, and this 60 cuts off the bottoms so that a large number of bottles are broken in handling the same in crates of this nature. My compensating shock absorbing means extending over a 65 portion of the partitions at a point where

the shock is directed on the bottoms entirely overcomes this undesirable feature.

The compensation provided by the resilient plate member 20 for the bottoms of the bottles B is obtained in the spacing of the 70 walls 21 of the same apart so that when the crate A is full of bottles the jar of the bottles against the partition walls is absorbed by the members 20 and the bottle bottoms 23 are prevented from striking together in a manner to cut off the same when the crates are jammed together as very often occurs in handling bottles of this nature in creameries. The compensators 20 also tend to hold the bottles steady and yet they are 80 not of a nature to take a large space in the crate. Thus I provide a means of protecting the bottles in a crate having substantially wire-like partitions of a narrow, thin 85 nature. I have found this feature of my invention to be very important in a practical crate of this nature.

In accordance with the patent statutes I have described the principles of operation of my particular construction of bottle crate and while I have illustrated a certain formation and assembly of the parts, I desire to have it understood that this is only illustrative and that the invention may be carried out by other means and applied to uses other than those above set forth within the scope of the following claims.

I claim:

1. A bottle crate comprising side walls, a series of longitudinal and transverse wire members adapted to form partition walls, and thin, sheet plate-like members each extending slidably over a plurality of said wire members between the corners of said partitions adapted to form a compensating means in the partition walls of said crate, said plate-like members extending more than half the width of said partitions.

2. A crate including, a series of partition walls, compensating members carried loosely by said partition walls between the corners of the partitions to protect a portion of the members carried in said crate against striking one against the other and to absorb the shock, each compensating member extending more than half the width of said partitions, and means to prevent excessive pivoting of said compensating members.

3. A bottle crate including, side walls, a series of intersecting partition walls, each of said partition walls formed of a series of superimposed wire members, and U-shaped spacer members looped over the wire member adjacent the bottom and extending below the bottom wire member of said series to space apart bottles in said crate.

4. A bottle crate including, side walls, a series of intersecting partition walls, each of said partition walls comprising superimposed parallelly extending members, U-

- shaped spacer members looped over some of said parallelly extending members, sides on said spacers converging apart away from the bend of said spacers, said spacers extending below the next lower parallel member to prevent excess pivoting thereof.
5. A bottle crate including, side walls, a series of intersecting partition walls, each of said partition walls comprising superimposed parallelly extending members, U-shaped spacer members looped over some of said parallel members, said spacers extending more than half the width of the partitions formed by said walls.
- 10 6. A crate including, a series of partition walls formed of a number of parallelly extending spaced members, compensating members each looped over a plurality of said spaced members, and corrugated walls on said compensating members.
- 15 7. A crate including, a series of partition members each formed of a number of parallelly extending spaced members, compensating members each looped over a plurality of said spaced members, and horizontally corrugated sides on said compensating members.
- 20 8. A spacer for bottle crate partitions including, a thin sheet member formed substantially U-shaped adapted to be looped over a crate partition member, and corrugations in said sheet member.

EDWARD M. PENNOCK.
